[57] CLAIM

The ornamental design for a forklift vehicle, as shown and described.

DESCRIPTION

FIG. 1 is a front right side perspective view of a forklift vehicle incorporating my new design;

FIG. 2 is a left side elevational view thereof;

FIG. 3 is a front elevational view thereof;

FIG. 4 is a rear elevational view thereof; and,

FIG. 5 is a top plan view thereof.

No claim is made to the bottom plan view of the vehicle.

FIG. 1

FIG. 2

FIG. 3

FIG. 4

FIG. 5
